[57] CLAIM

The ornamental design for a infant's activity center, as shown and described.

DESCRIPTION

FIG. 1 is a perspective view of an infant's activity center showing our new design;

FIG. 2 is a side elevational view thereof;

FIG. 3 is an elevational view from the opposite side thereof;

FIG. 4 is a front elevational view thereof;

FIG. 5 is a rear elevational view thereof;

FIG. 6 is a top plan view thereof; and,

FIG. 7 is a bottom plan view thereof.

The portions shown in broken lines in FIG. 1 are for information only and form no part of the instant design.
